UNITED STATES PATENT OFFICE

WALTER L. CHURCH, OF HOUSTON, TEXAS

CASING HEAD FOR OIL AND GAS WELLS

Application filed March 8, 1929. Serial No. 345,411.

This invention relates to new and useful improvements in a casing head for oil and gas wells.

One object of the invention is to provide a casing head of the character described which is designed to be attached to the upper end of a casing in a well and which is equipped with means for forming a seal between the casing and the drill stem or other inner pipe in the casing so as to effectively prevent the escape of oil or gas from the well between the casing and inner pipe or stem.

Another object of the invention is to provide means, in a casing head, which is normally in inactive, or open position so as not to interfere with the usual operations carried on through the casing, but which may be moved either manually or mechanically into position about the inner pipe or drill stem so that as the inner stem is lowered a coupling thereof will land on the packing or sealing means employed, and carry the same down into the bowl or seat in the casing head spider to form a fluid tight seal between said seat and the inner pipe or stem.

A further feature of the invention resides in the provision of means for securing said seal, or packer, in the casing head seat.

With the above and other objects in view this invention has particular relation to certain novel features of construction, operation and arrangement of parts an example of which is given in this specification and illustrated in the accompanying drawings, wherein:

Figure 1 shows a side elevation of the device, partly in section, with the packer, or seal, in its upper position.

Figure 2 shows a side elevation thereof, showing the packer in lower or sealing position, and shown partly in section.

Figure 3 shows an upper end view of the device partly in section, and shown in open or inactive position, and

Figure 4 shows an upper end view of the seal.

Referring now more particularly to the drawings, wherein like numerals of reference designate similar parts in each of the

figures the numeral 1 designates a casing adapted to be set in a well bore. Attached to the upper end of this casing there is a tubular spider 2 having the lateral flow line connections 3, 3. The upper end of this spider forms an enlarged bowl 4 having an inside annular seat 5 and the upper end of the spider is formed with an annular outwardly extending flange 6. There is a tubular holder formed of the similar confronting sections 7, 7, arcuate in cross sectional contour. The upper ends of these sections have the arcuate inwardly extending flanges 8, 8 which are provided with the inside registering notches 9, 9 to receive the inner pipe, or drill stem 10, whose sections are connected by the couplings, as 11. The lower ends of the respective sections 7 have the external flanges 12, 12 having the internal arcuate cavities 13, 13 to receive the external flange 6. This flange forms, in effect, a track on which the sections 7, 7 are supported and ride.

Within the respective holder sections are the sleeve sections 14, 14, arcuate in cross sectional contour and each of which is composed of the expandible packing 15, and the upper and lower arcuate metal sections 16, 17 above and below said packing, and suitably secured thereto. Each sleeve section has the downwardly and outwardly sloping face 18 on which a wedge shaped dog 19 is mounted to slide. The outer face of each dog is toothed to engage the inner wall of the holder 7. The dogs 19 preferably have a dovetailed connection with corresponding sleeve sections.

Around the holder there is an elliptical yoke 20 which is attached, at one end, to one of the sections 7 by means of a bolt 21 and an actuating shaft 22 is threaded through the other end of the yoke 20 and its inner end has a swivelling connection with the other section 7. The sections 14 are normally held in upper position, against the flanges 8 by means of frangible pins 23, 23.

By rotating the shaft 22 in one direction the holder sections may be moved apart, or into inactive position, as shown in Figure 3, and by rotating the shaft 22 in the other di-

rection the holder sections may be moved together to close the sleeve sections 14 about the inner pipe 10, as shown in Figures 1 and 2 to form a tight seal.

5. During drilling operations the holder, and sleeve sections carried thereby, are moved into open, or inactive position, as shown in Figure 3 so as to be out of the way but in case strong pressure is encountered in the 10 well the holder may be actuated, as above indicated, to close the sleeve sections about the pipe 10 and the inside pipe 10 then lowered to land the coupling 11 on the sections 14, as shown, in Figure 1. The weight of 15 this inside pipe will shear the pins 23 and the sleeve sections will be lowered onto the seat 5 and the weight of the pipe carried by 20 said sleeve sections will expand the packing 15 out against the surrounding walls of the 25 bowl 4, as shown in Figure 2 and a tight joint will thus be formed between the casing and inner pipe to prevent the escape of the oil or gas between them and the fluid in the casing around the inner pipe may be relieved 30 through either or both of the lines attached to the connections 3 and the oil in the well may be controlled and discharged from the well through the inner pipe 10 in the usual way.

30. The sleeve sections 14, when in lower position are securely locked against upward movement in the bowl by the dogs 19.

The sections 14 are held in transverse alignment in any suitable manner, as by 35 means of dowel pins 24, carried by each section 14 and projecting into sockets 25 in the abutting faces of the other section 14.

What I claim is:—

40. 1. A casing head including a tubular spider adapted to be connected to a casing in a well bore, a bowl at the upper end of the spider having an internal seat therein, a sectional holder on the upper end of the spider formed of confronting sections having a 45 slideable connection with the spider and movable toward and from each other, arcuate sealing means in the holder sections formed to surround an inner pipe and adapted to lodge on said seat, and means for actuating the 50 holder sections toward and from each other.

55. 2. A casing head including a tubular spider adapted to be connected to a casing in a well, a bowl at the upper end of the spider, a seat beneath the bowl, a holder above the bowl, sealing means in the holder, formed to surround an inner pipe, frangible means normally retaining said sealing means in said holder.

60. 3. A casing head including a tubular spider adapted to be connected to a casing in a well, a bowl at the upper end of the spider, an annular seat beneath the bowl, a holder above the bowl, sealing means in the holder, formed to surround an inner pipe, frangible 65 means normally retaining said sealing means

in said holder, the upper end of the sealing means being exposed so that a coupling of the inner pipe may land thereon, in case of the descent of said pipe, to effect the breaking of the frangible means and the landing 70 of the sealing means on said seat.

4. A casing head including a tubular spider adapted to be connected to a casing in a well, a bowl at the upper end of the spider, a seat below the bowl, a holder on the spider formed of sections, means for adjusting said sections toward and from each other, confronting sealing means in the holder formed to surround an inner pipe in the casing, means for retaining the sealing means in the holder sections, said holder being formed to expose the upper ends of the sealing means, when the sealing means are adjusted into position about the inner pipe. 75

5. A casing head including a tubular spider adapted to be connected to a casing in a well, a bowl at the upper end of the spider, a seat below the bowl, a holder on the spider formed of sections, means for adjusting said sections toward and from each other, confronting sealing means in the holder formed to surround an inner pipe in the casing, means for retaining the sealing means in holder sections, said holder being formed to expose the upper ends of the sealing means, when the sealing means are adjusted into position about the inner pipe, to permit a pipe coupling to land thereon and force the sealing means into said bowl and onto said seat, upon 80 descent of the inner pipe. 85

6. A casing head including a tubular spider adapted to be connected to a casing in a well, a bowl at the upper end of the spider, a seat below the bowl, a holder on the spider formed of sections, means for adjusting said sections toward and from each other, confronting sealing means in the holder formed to surround an inner pipe in the casing, means for retaining the sealing means in the holder sections, said holder being formed to expose the upper ends of the sealing means, when the sealing means are adjusted into position about the inner pipe, to permit a pipe coupling to land thereon and force the sealing means into said bowl and onto said seat, upon descent of the inner pipe and said sealing means and holder being provided, one with an engaging device arranged to engage the other, to prevent upward movement of the sealing means in said bowl. 100

7. A casing head including a tubular spider adapted to be connected to the upper end of a casing in a well, a seat within the spider, a holder above the spider, a sealing means within the holder above said seat, said holder and sealing means being formed to surround an inner pipe in the casing and being adjustable into active position to close the sealing means closely about the pipe and into inactive position to space the sealing means 110 115 120 125 130

from said pipe the upper end of the sealing means being exposed, when said means are in said active position, to permit a shoulder on the inner pipe to land thereon to seat 5 said sealing means on said seat.

8. A casing head including a tubular spider adapted to be connected to the upper end of a casing in a well, a seat within the spider, a holder above the spider, a sealing means 10 within the holder, said holder and sealing means being formed to surround an inner pipe in the casing and being adjustable into active position to close the sealing means closely about the pipe and into inactive position to space the sealing means from said pipe, and frangible means normally retaining the sealing means in the holder. 15

9. A casing head including a tubular spider adapted to be connected to the upper 20 end of a casing in a well, a seat within the spider, a holder above the spider, a sealing means within the holder, said holder and sealing means being formed to surround an inner pipe in the casing and being adjustable 25 into active position to close the sealing means closely about the pipe and into inactive position to space the sealing means from said pipe, frangible means normally retaining said sealing means in the holder, said sealing 30 means, when in active position, being in position to receive a pipe coupling thereon, upon descent of the pipe, whereby said frangible means may be broken by the weight of the pipe and the sealing means landed on 35 said seat.

10. A casing head including a tubular spider adapted to be connected to a casing in a well, a bowl at the upper end of the spider, a seat beneath the bowl, a holder above the 40 bowl, sealing means in the holder, formed to surround an inner pipe, frangible means normally retaining said sealing means in said holder, said holder being formed of adjustable sections and characterized by the provision of a yoke therearound to which one holder section is connected and an adjusting shaft operatively connected with said yoke and with the other holder section. 45

11. A casing head including a tubular spider adapted to be connected to a casing in a well, a bowl at the upper end of the spider, a seat beneath the bowl, a holder above the bowl, sealing means in the holder, formed to surround an inner pipe, means normally 50 retaining said sealing means in said holder, the upper end of the sealing means being exposed so that a coupling of the inner pipe may land thereon, in case of the descent of said pipe, to effect the breaking of the retaining means and the landing of the sealing means on said seat, and means carried by the sealing means and engageable with the walls of the holder to retain said sealing means against said seat. 60

65 12. In a casing head attached to a casing

in a well bore and having an inside seat; a seal shaped to surround an inner pipe in the casing said seal being movable into inactive position in spaced relation to the inner pipe to permit said inner pipe to pass therethrough and being also movable into active position to closely surround said inner pipe, the upper end of said seal when in said active position, being exposed to permit a shoulder on the inner pipe to land on said upper end 70 to seat said seal on said seat.

13. In a casing head attached to a casing in a well bore and having an inside seat; a seal shaped to surround an inner pipe in the casing said seal being movable into inactive 75 position in spaced relation to the inner pipe to permit said inner pipe to pass therethrough and being also movable into active position to closely surround said inner pipe, the upper end of said seal when in said active 80 position, being exposed to permit a shoulder on the inner pipe to land on said upper end to seat said seal on said seat, and means for moving said seal into either active or inactive position. 85

In testimony whereof I have signed my name to this specification.
